UNITED STATES PATENT OFFICE.

OAKLEY S. WALKER, OF WORCESTER, MASSACHUSETTS, ASSIGNOR TO THE WORCESTER POLYTECHNIC INSTITUTE, OF SAME PLACE.

TWIST-DRILL-GRINDING MACHINE.

SPECIFICATION forming part of Letters Patent No. 425,839, dated April 15, 1890.

Application filed October 3, 1889. Serial No. 325,948. (No model.)

To all whom it may concern:

Be it known that I, OAKLEY S. WALKER, a citizen of the United States, residing at Worcester, in the county of Worcester and 5 State of Massachusetts, have invented certain new and useful Improvements in Twist-Drill-Grinding Machines, of which the following is a specification.

My invention relates to drill-grinding machines, but more particularly to that class called "twist-drill grinders," the object being to simplify their operation and to produce improved results.

To these ends my invention consists of the 15 construction and arrangement of the novel mechanism hereinafter fully described.

In grinding a drill the usual method employed in presenting it to the grinding-wheel is the swinging method, where the drill is 20 held in a drill-holder which is arranged to swing upon an axis, the said axis not being coincident with the center line of the drill as it lies in the holder. The drills are held so that the ends to be ground all extend beyond 25 this axis toward the grinding-wheel, the ground surface obtained being a curved surface with the said axis for a center, and the radius of the curve always depending upon the distance of the end of the drill from said axis, 30 which is obvious. It is also obvious that drills of differing diameters cannot well be ground to curves of the same radius. It follows then that a machine to grind drills properly should have some means of measuring 35 the adjustment of the drill-holder away from the axis corresponding to the size of the drill to be ground. A graduated scale with a pointer arranged to move along the same has been employed to accomplish these ends.

40 This system is faulty, inasmuch as it requires the machine operator to determine the size of each drill before grinding, which is very often difficult to accomplish, as many drills are not marked and would require measuring in order to determine their sizes.

45 In my invention I obtain the proper adjustment of the drill-holder by means of an improved device, which performs the operation of simultaneously caliperizing a drill and 50 giving the drill-holder the proper adjustment for the same. I accomplish this by placing

the drill between the jaws of a peculiar-shaped gage attached to the drill-holder, thus making each drill adjust the machine according to its diameter. Other improvements 55 accomplished in my improved drill-grinding machine are: a combination with the drill-holder of a convenient truing device to maintain the truth of the grinding-wheel, an adjustable stop to limit the oscillating movement of the drill in grinding, and an improved device to provide for the holding and accurate grinding of drills constructed with two or more cutting-lips, including flat drills and drills with either straight or spiral 60 grooves. These various improvements I will now proceed to explain with the aid of the accompanying drawings, in which like letters of reference indicate the same parts in each.

Figure 1 is a part section and elevation of 70 the drill-grinding machine with a small drill in place, showing the method of setting the drill-holder by means of a graduated scale, the graduated scale being disclaimed in this application. Fig. 2 is an elevation of the same 75 style of drill-holder, and with the emery-wheel is shown detached from the machine and shows a larger drill in place. Fig. 3 is an elevation of the drill-holder, showing the operation of my new adjusting-gage. Fig. 4 80 is an elevation similar to Fig. 3. Figs. 5 and 6 are plan views of the drill-holder, showing the adjusting-gage more clearly. Fig. 7 is a diagram explaining the principle of the adjusting-gage. Fig. 8 is an elevation of the 85 drill-grinding machine, illustrating the operation of the truing device. Fig. 9 is an elevation of a portion of the drill-holder drawn apart to illustrate the action of the adjustable stop. Fig. 10 is an end view of the drill-holder, showing an ordinary two-lipped twist-drill in place. Fig. 11 is a similar view showing a three-lipped drill in place. Fig. 12 is an end view of the drill-holder and shows the method of holding a four-lipped drill in the 90 V-shaped holder by means of an adjustable lateral support. Fig. 13 is a view similar to the three preceding and shows the method of holding a flat drill in place.

A is the main standard of the machine, and 100 a the grinding-wheel. The parts B, D, and C, with their attachments, constitute the drill-

holder, which is held in place in the main standard A by means of the clamping-screw A', which compresses a split hub on the standard and binds the sleeve portion B of the drill-holder to any part of its length, so that its longitudinal position may be rapidly adjusted.

5 B' is a collar fastened to the sleeve B by the set-screw b, and may be adjusted at pleasure.

10 B² is a ball-handle attached to the inclined head, which forms one end of the sleeve B. This inclined head is bored for the reception of a shaft forming a part of the oscillating bracket C. The center of this shaft is represented by the axial line x y. This shaft extends below the bottom of the inclined head, and upon the end thus protruding is mounted a collar C', adjustably fastened by 15 a set-screw c and having an upward-projecting finger c² attached to its periphery, and which extends above sufficiently to come in contact with another projection b² upon the inclined head of the sleeve B when the collar is made to rotate with the oscillating bracket C. Another projection c' upon the oscillating bracket C similarly comes in contact with a second projection b' upon the top of the inclined head. These projections c' 20 and b' form a positive stop to limit the oscillating movement of the bracket C in the direction to the left, while the movement to the right, being limited by the adjustable projection c², permits an adjustable limitation 25 of the oscillating movement toward the right hand, which is a necessary requirement in grinding drills of more than two cutting-lips.

30 Upon the top of the oscillating bracket C is mounted the drill-holder top D, adjustably fastened by the clamping-screw D² and arranged to be adjusted to and from the emery-wheel when the screw D² is loosened.

35 D' is a longitudinally-adjustable support for the shank of the drill held by screw D³, working through a slot in the drill-holder top D.

40 E is the drill-stop, similarly adjusted and fastened by screw E².

45 e, E', and e' are adjustable portions of the drill-stop E. The sleeve E' passes through a 50 split hub at the top of the main support of the drill-stop E and is adjustably clamped by means of the screw e². The spindle e has a longitudinal movement in the sleeve E' and is operated against the end of the drill by 55 means of the thumb-screw e' for the purpose of feeding the drill against the grinding-wheel.

60 The end of the drill-holder top D toward the grinding-wheel is provided with a lateral projection through which is bored a hole for the reception of the wheel-truing device f', adjustably held in place by the set-screw f². This truing device may be an ordinary diamond set in a cylindrical holder, or any other 65 instrument suitable for truing emery-wheels.

The dotted lines in Fig. 8 show another position assumed by the drill-holder in passing

70 across the emery-wheel while truing the same, which operation will be fully explained farther on.

75 In Figs. 1 and 2 are shown the different positions of the ends of the different-sized drills from the axial line x y, and the said figures also show the method of adjusting the drill-holder top by the graduated-scale system. Fig. 3 shows the same adjustment as in Fig. 1, but is accomplished by means of my new adjusting-gage. Fig. 4 shows the same adjustment as in Fig. 2, also by means of the adjusting-gage. D⁴ and C⁴ are the jaws of the 80 adjusting-gage, and are more fully understood by referring to Figs. 5 and 6.

85 D⁴ is attached to and forms a part of the drill-holder top D, and C⁴ is attached to the oscillating bracket C, and is therefore stationary, while D⁴ is moved along with the drill-holder top in adjusting the same for a drill. The edges of drill contact of these gage-jaws in this case are approximately parallel, and 90 their angularity with the line of movement of the drill-holder top depends upon the requirements of the machine.

95 The drill-holder top D, it will be seen, does not move at right angles to the axial line of oscillation x y. It follows, then, that in order to move the end of the drill a certain distance beyond the axis the drill-holder top must be moved a still greater distance. It is possible, however, to change the direction of the adjustment, so that it shall be at right 100 angles or at other angles with the axial line x y, in which case a modification of the adjusting-gage above shown would be necessary, as will be shown farther on.

105 It having been determined by the construction of the machine that the drill-holder top needs to be moved along its line of movement three inches when the drill to be ground is two inches in diameter, it is obvious that the ratio of adjustment to the diameter of the 110 drill is as three is to two. With this proposition as a starting-point, the explanation of the diagram shown in Fig. 7 is as follows: The line O' O represents the edge of drill-contact of the gage-jaw C⁴, and must be conceived as stationary. The line N' N and the dotted line M' M represent different positions of the edge of drill-contact of the gage-jaw D⁴ as it is adjusted in the direction O M corresponding to the line of movement of the 115 drill-holder top. Conceiving the lines N' N and O' O to be in contact at the start, an adjustment of the distance from O to N—say one and one-half inch—will bring the lines O' O and N' N a certain distance apart measured by the perpendicular line O L, the length of 120 which must be one inch, because as one and one-half is to one so is three to two, according to the proposition above mentioned. If, now, the line N' N is again adjusted a distance N M equal to O N, it is obvious that the distance N L' will be equal to the distance O L, and the 125 drill caliper by the lines M' M and O' O will be two inches in diameter, or twice the 130

distance O L, while the distance O M (corresponding to the whole adjustment of the drill-holder) will be twice the distance O N, or three inches, which conforms to the ratio assumed.

5 It is obvious that any drill calipered by the gage-jaws will adjust the drill-holder top in the same ratio as above demonstrated. It is also obvious that any difference in the angle of the lines O' O and N' N with the line 10 of adjustment O M would change the ratio of the adjustment to the diameter of the drill, and if the said lines O' O and N' N were at right angles to the line of adjustment O M the ratio would be unity and the adjustment 15 would equal the diameter of the drill. If the lines of drill-contact of the gage-jaws D⁴ and C⁴ (represented by the lines O' O and N' N of the diagram Fig. 7) were other than parallel—for instance, inclined toward each 20 other—the required result could be obtained, but the drill would have a third point of contact—i. e., against the side of the drill-holder top—and the drill would have to be withdrawn longitudinally. In a drill-grinder 25 where the adjustment of the drill-holder top is at or near a right angle to the axial line of oscillation, the adjustment might be less than the diameter of the drill, in which case the edges of the gage-jaws should diverge and 30 form a V when closed together. I do not therefore confine myself to any particular ratio of adjustment of drill-holder, nor to a particular angle of gage-jaw.

In Fig. 10 at T' is shown an ordinary twist-drill, held in correct position by the lip-rest i, fastened to the V-shaped holder by the screws s. The lip-rest i is disclaimed in this application.

In Figs. 12 and 13 are shown the functions of 40 the adjustable lateral support I for holding four lipped drills and flat drills in a V-shaped holder. I is a thin piece of steel plate working through a slit in the side of the drill-holder top D, and may be placed flush with the inner 45 surface of the holder, as in Fig. 10, or, as in Fig. 12, moved up to support the drill upon one side, the device being held in place in each position by the set-screw J. (Shown in Fig. 6.) In Fig. 13 the support is placed on 50 the opposite side of the drill from the position shown in Fig. 12. By reference to Figs. 11 and 12 it will be seen that unless the oscillating movement of the drill-holder top and the drill is limited the drill-lips T² and T³ would 55 come in contact with the grinding-wheel when swung far enough in that direction. The adjustable stop c², previously explained, is designed to obviate this difficulty.

The operation of my improved drill-grinder 60 is as follows: The clamping-screw A' is first loosened and the drill-holder is drawn out at a distance away from the grinding-wheel. The clamping-screw D² is then loosened and the drill-holder top moved until the drill to be 65 ground will pass between the jaws C⁴ and D⁴ of the adjusting-gage. The drill-holder top is thus properly adjusted for the diameter of

the drill, and is then rigidly clamped to the oscillating bracket C by the screw D². The drill is then placed in the V-shaped supports 70 of the drill-holder, with the lip to be ground extending slightly beyond the lip-rest i, with the edge of the groove of the drill resting against it. The drill-stop E is then moved up against the shank end of the drill and clamped 75 by means of the screw E². The clamping-screw A' is now loosened and the whole drill-holding device is moved up until the point of the drill nearly comes in contact with the grinding-wheel. Then the clamping-screw A' 80 is tightened. The drill is now held in position with one hand, while with the other the drill is fed to the grinding-wheel by means of the thumb-screw e' acting against the end of the spindle e, and the drill-holder top D and 85 guide-bracket C are at the same time oscillated to the right and left against the stops, as previously explained. The oscillating portion of the drill-holder works about the axial line x y, which movement may be in a helical 90 direction toward the grinding-wheel to give the proper clearance to the drill, or the drill may be so held (by the construction of the machine) that its center line prolonged would never meet the axial line of oscillation. Thus, a 95 ground surface being obtained eccentric with the drill, the necessary backing off (or clearance) would be obtained. These and various other methods of obtaining clearance having been previously covered, they are disclaimed 100 in this application.

To true up the grinding-wheel, the truing device f' is adjusted at a suitable distance beyond the end of the drill-holder, and is fastened by means of the set-screw f². The 105 drill-holder is now moved up until the truing device will touch the lowest surface of the wheel. Then the collar B' is fastened in contact with the hub of the main support A by means of the set-screw b.

The clamping-screw A', being left loose with one hand grasping the ball-handle B², and with the other holding the oscillating portion of the drill-holder against the stop on the left hand, the whole drill-holder is swung 115 about the center of the sleeve B, the collar B' keeping the sleeve in place by its continuous contact with the casting A. The truing device f' thus passes across the grinding-wheel in a plane, and by its cutting action 120 accurately trues the surface of the wheel. When not in use the truing device is pushed back and fastened out of the way by the set-screw f², as shown in Figs. 3 and 4.

Having now described my invention, what 125 I claim as new, and desire to secure by Letters Patent, is as follows:

1. The combination, with a twist-drill-grinding machine, of the drill-holder top D and the oscillating bracket C, provided, respectively, with the projecting gage-jaws D⁴ and C⁴, arranged to simultaneously caliper the drill to be ground and to axially adjust the drill-holder, as above set forth.

2. In a twist-drill-grinding machine, the combination, with a V-grooved drill-holder, of the parallel gage-jaws D⁴ and C⁴, whose contact-faces are inclined to the line of their adjustment, for the purpose above described.
3. The combination, with the drill-holder top D and oscillating bracket C, of the adjustable stop c², arranged to limit the oscillating movement of the drill-holder, as and for the purpose set forth.
4. The drill-holder top D and the oscillating bracket C, mounted upon the sleeve B, combined with the adjustable collar B' and the emery-wheel truing-tool f', for the purpose described.
5. The combination of the main supporting-standard A with the emery-wheel truing-tool

f', suitably mounted upon and swinging with the sleeve B, for the purpose set forth.

6. The combination, with the drill-holder top D, mounted upon the oscillating bracket C, of the adjustable stop c² and the lateral drill-support I, arranged as and for the purpose above described.

7. An oscillating drill-holder provided with a lip-rest i, combined with the adjusting gage-jaws D⁴ and C⁴, the oscillating bracket C, and the adjustable stop c², as and for the purpose set forth.

OAKLEY S. WALKER.
